(57) **CLAIM**

The ornamental design for a cabinet light, as shown and described.

DESCRIPTION

FIG. 1 is a front perspective view of a cabinet light showing my new design.

FIG. 2 is rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is an enlarged view of a cabinet light taken from the part in FIG. 1.

FIG. 10 is a perspective view of the cabinet light in an alternate configuration of use where the cabinet light is pulled out; and,

FIG. 11 is another perspective view of the cabinet light shown in an environment of use.

The broken lines illustrate portions of the cabinet light that form no part of the claimed design. The use of broken lines in FIG. 11 indicates environmental structure that forms no part of the claimed design. The dash-dot broken lines surrounding the detail views in FIGS. 1 and 9 are for annotative purposes only and form no part thereof.
